UNITED STATES PATENT OFFICE.

PIERRE PLANTINGA, OF CLEVELAND, OHIO.

APPARATUS FOR OPERATING WATER-GAS SETS.

Application filed November 6, 1920. Serial No. 422,352.

To all whom it may concern:

Be it known that I, PIERRE PLANTINGA, a citizen of the United States, resident of Cleveland, county of Cuyahoga, and State of Ohio, have invented new and useful Improvements in Apparatus for Operating Water-Gas Sets, of which the following is a specification, the principle of the invention being herein explained and the best mode in which I have contemplated applying that principle, so as to distinguish it from other inventions.

My invention relates to apparatus for automatically operating water gas sets.

As it well known to those skilled in this art,—in the manufacture of water gas, as it is commonly practised, generating apparatus is utilized provided with a number of valves which must be operated in proper sequence and periodically, in order to effect the alternate "blows" and "runs" forming the necessary cycle of operations. There are a number of these valves, and inasmuch as one cycle of operation does not take over seven or eight minutes, the valves must be frequently manipulated. Furthermore, inasmuch as it is important that the valves be manipulated at exactly the right moment, manual operation thereof is frequently quite detrimental to satisfactory gas-making. The valves commonly forming part of this apparatus are six in number, and in the suggestive exemplification of this standard feature of the invention in the accompanying drawings I have shown six valves, but different numbers of valves are used in different gas-making operations. These valves are known as, generator and carbureter blast valves, a superheater stack valve, a generator steam valve, a carbureter oil valve, and a reversing valve. This latter valve, including so-called upper and lower hot gas valves, is utilized for reversing the direction of travel of the gas through the generator to provide either a so-called "up-run" or a so-called "down-run" during the gas-making period, which is the second period of operation during one cycle of operations. During the first period of operation, commonly called the "blow," the generator and carbureter blast valves are open and the stack valve is open, and the operation continues until the temperature of the generator fuel and the checker brick is high enough for gas making. This period of operation commonly takes three of four minutes. During

the second period, or run, the blast valves are closed and the stack valve closed, and the steam and oil valves are open. This period of operation also consumes three or four minutes. Sometime during this period, the reversing valve is operated to change the direction of gas run through the generator, the up and down runs varying for different gas-making operations. All of this is well known to those skilled in the art, as is also the fact that the manipulation of the valves is not as simple as hereinbefore briefly noted, the "blow" and "run" operations each requiring several detailed manipulations of the valves, in order properly to carry out the cycle.

Other apparatus intended automatically to actuate these valves is known to those skilled in the art, so that it is the design of this invention to simplify and perfect the apparatus for accomplishing this purpose. Particularly it is the design of this invention to directly connect automatically operated actuating means to certain elements controlling the operations of the several apparatus valves.

The annexed drawings and the following description set forth in detail certain means embodying my invention, the disclosed means, however, constituting but one of the various mechanical forms in which the principle of the invention may be employed.

In said annexed drawings:—

Figure 1 represents a side elevation of water gas apparatus, a suggestion of my improved means for automatically operating the same being therein indicated;

Figure 2 represents a top plan view taken upon the plane indicated by the line II—II in Figure 1;

Figure 3 represents an end elevation of my improvement, taken from the plane indicated by the line III—III, Figures 1 and 4;

Figure 4 represents a side elevation taken from the planes indicated by the lines IV—IV in Figure 3;

Figure 5 represents a transverse section, taken in the plane indicated by line V—V, Figure 4;

Figure 6 represents a fragmentary, transverse, vertical section taken in the plane indicated by the line VI—VI, Figure 4;

Figure 7 represents a top plan view of a nest of valves forming part of my invention; and

Figure 8 represents a vertical, longitudinal section of one of said valves, taken in the plane indicated by the line VIII—VIII, Figure 7.

- 5 Referring to the annexed drawings, in which the same ordinals designate like parts in the several views, 1 indicates the generator, 2 the carbureter, 3 the superheater, 4 the hydraulic seal, and 5 the gas outlet of 10 water gas apparatus. A stack valve is indicated by 6, an upper hot gas valve by 7, a lower hot gas valve by 8, a carbureter blast valve by 9, a reversing steam valve by 10, a carbureter oil valve by 11, a generator blast valve by 12, and a generator steam valve by 22. Hydraulic cylinders are provided for operating these valves, 13 and 14 indicating, respectively, a cylinder and plunger for the stack valve 6. The 15 actual connection of the plunger 14 with the stack valve 6 is effected by a link 15 and an arm 16 pivotally connected together. A cylinder and plunger for the generator blast valve 12 are indicated by the ordinals 17 and 18. The plunger 18 is integral with the stem of the generator blast valve 12. A cylinder and plunger for the carbureter blast valve are indicated, respectively, by the ordinals 19 and 20. A cylinder and 25 plunger for the valve 22 is indicated by the ordinal 21. This hydraulic cylinder 21 operates the generator steam valve 22, which controls entirely the steam entering by the line 22'. A cylinder and plunger for the oil valve 11 are indicated respectively by the ordinals 23 and 24. A cylinder and plunger for the upper hot gas valve 7 are indicated respectively by the ordinals 25 and 26. Steel bars 27 are connected to the 30 plunger 26 and carry at their outer free end a counterweight 27'. Secured intermediately of the ends of the bars 27 are links 28 which are pivotally mounted at their other ends upon the casing of the upper hot gas valve 7. The stem 29 of the lower hot 35 gas valve 8 is secured to the steel bars 27 intermediately the counterweight 27' and the point 28' at which the pivot links 28 are secured to said steel bars 27. The steel bars 27 are also secured to the steam valve 10 by means of a connection 30 so that the reciprocal movements of said bars 27 will effect the reversing of the steam valve 10, which is a three-way valve and controls the 40 direction of the steam through the generator 1 to effect the up or down run of gas, as desired. A line for the air blast is indicated by the ordinal 31, and this blast is controlled by the generator blast valve 12. 45 The blast enters the generator 1 at the bottom, and the top outlet from the generator is indicated by the ordinal 32. This outlet is controlled by the upper hot gas valve 7. A bottom outlet from the generator 1 is indicated by the ordinal 33, and this outlet 50

is controlled by the lower hot gas valve 8. A gas passage from the generator 1 to the carbureter 2 is indicated by the ordinal 34. The bottom outlet 33 from the generator 1 connects into the bottom of the gas passage 55 34 beyond the position of the upper hot gas valve 7. In the position of the several elements 7, 8, 10, 27, 30, etc., shown in Figures 1 and 2 the apparatus valves are arranged for an "up run". When the plunger 26 of 60 the cylinder 25 is actuated downwardly, resulting in the closing of the upper hot gas valve 7, the bars 27 will move about the pivot of the link 28, and the connection 30 will reverse the steam valve 10 and the stem 29 of the valve 8 will be raised so as to open the lower hot gas valve 8, whereby the valve arrangement will be such as to reverse the direction of gas flow through the generator 1, resulting in a "down run".

The gas-generating operations so far described are well-known to those versed in the art, and I shall now describe automatically operated mechanical means for causing the operation in proper sequence and periodically of the several hydraulic cylinders. These cylinders are controlled directly by a nest of hydraulic valves 36, which determine the direction of fluid movement to and from the hydraulic cylinders. 65 Pipes 35 and 35', Figure 8, connect the several hydraulic cylinders with the several valves 36, there being a pair of said pipes for each cylinder, the same being illustrated diagrammatically in Figures 1 and 2, the pipe 35 leading to one end of the hydraulic cylinder, and the pipe 35' leading to the other end of the hydraulic cylinder. The action of the hydraulic valve 36 is well known, and will be only briefly described. 70 A nest of the valves is shown in Figure 7, and a transverse, vertical section through one of the valves is shown in Figure 8. From any suitable source, water under pressure enters the inlet manifold 37, and is discharged from the valves 36 through the exit manifold 38. A reciprocating plunger 39 controls the direction of movement through the valve 36 of the water, the position of said plunger 39, Figure 8, being that 75 in which the water is presumed to flow from the valve 36 to one end of one of the apparatus-valve-controlling cylinders to open the valve, and to return to the valve 36 from the other end of the apparatus-valve-controlling cylinder.

It is the design of my invention to reciprocate the hydraulic valve pistons 39 by direct connection with automatically operated and properly timed mechanical means. 80 To each piston 39 is secured an operating rod 40, Figure 4, the outer end of which is tapped into a connection 41 which is pivotally connected by the link 42 to the end of the square plunger 43 mounted in 85

bearings 43' supported in a frame 51. The faces of the plunger are mounted at a forty-five degree (45°) angle to a vertical plane, as plainly shown in Figure 5, and the 5 plunger is held in the bearings 43' by means of plates 43², as plainly shown in said Figure 5. To the other end of the square plunger 43 is pivotally and detachably secured a link 44 which in turn is secured 10 to an operating handle 45 intermediately the ends of the latter, one end of said handle 45 being pivotally secured to the bracket 46 supported by the frame 51, as plainly shown in Figure 4. The purpose of the 15 handle 45 will be hereinafter fully explained. It will be remembered that there is provided one plunger 43 and the other connected elements for each of the valves 36.

20 Referring particularly to Figures 1 and 2, suitable primary power means, such as the motor 47, is therein shown, the motor shaft being indicated by the ordinal 48, and a suitable change gear set, by the ordinal 25 52. A shaft 52', which is rotated at the desired speed by the motor 47, in turn operates a silent chain 49 which rotates a shaft 50, Figure 3, suitably mounted in the frame 51. An eccentric 53 secured to the shaft 30 50 operates a rod 56 secured at its outer end 57 to a bar 58 pivotally mounted upon a shaft 55, hereinafter more fully described. Upon the outer end of the bar 58 is mounted a pawl 59. The shaft 55 is also suitably 35 rotatably supported in the frame 51 and thereto is secured a ratchet wheel 54 which is adapted to be turned one tooth, at every revolution of the shaft 50, by the pawl 59. Also secured to the shaft 55 are six pairs of 40 disks 60, each having one or more peripheral notches 61. There is provided one pair of these disks 60 for each of the plungers 43 reciprocating the valve pistons 39.

45 Referring to Figure 3, it will be noted that one end of the shaft 50 is provided with a crank arm 62 which is secured at its outer end to a vertical connecting rod 63. Mounted in the frame 51 and extending transversely thereof is a bar 64 to which 50 is secured an arm 65 which at its other end is pivotally secured to the bar 63, by means of a pin 66. Secured to the bar 64 is a downwardly extending arm 67 having pivotally secured to its lower end a pair of dogs 55 68 whose outer ends are pivoted to the lower ends of a pair of upwardly extending bars 69. The upper ends of these bars 69 are pivotally secured to a pair of pawls 70 and 71, respectively, said pawls being 60 formed at one end with upwardly extending fingers 70' and 71', respectively, and being mounted on a pair of rods 72 intermediately the fingers 70' and 71' and the pivotal connection of the pawls with the 65 upper ends of the bars 69. By means of springs 73, secured to the pawls at the end thereof opposite that upon which the finger 70', is formed, the pawl tends to lie in a position in which the finger is in its most elevated position. These fingers 70' and 71' intersect the notches 61 formed in the respective disks 60 of the pair of disks. There is provided a set of the elements 75 77 and 68 for each of the hydraulic valves 36. The purpose of the pair of bars 69 and associated elements is to control the movements of the actuating means 40, 43, etc., in both directions. Suitably secured in the frame 51 and transversely thereof, are a pair of bars 78 and 83. Upon the bar 78 is rigidly 80 mounted a locking-out lever 74 formed with a catch 75 within which is mounted a spring-controlled pin 76 adapted to register with a pair of holes 77 formed in the frame 51. Also fixedly mounted upon the respective 85 bars 78 and 83 are a pair of locking-out dogs 79. A downwardly extending link 80 is secured to the locking-out lever 74 and pivotally mounted upon the outer end of this link 80 are links 81 to whose other end is pivotally secured a lever 82. This lever 82 is fixedly mounted upon the rod 83. When the spring-controlled pin 76 is removed from the hole 77 in which it is 90 shown as being mounted in Figure 4, and the locking-out lever 74 then moved across the face of the frame 51 and the pin 76 locked in the empty hole 77 shown in Figure 4, the free outer ends of the locking-out dogs 79 are turned upwardly and intersect 95 the spring-connected end of the pawls 70 and 71, whereby the other ends of the pawls are turned downwardly about the rods 72, so that it is impossible for the fingers 70' and 71' to be pressed into the notches 61 formed 100 upon the disks 60.

105 The afore-described apparatus rocks the arms 67 at every revolution of the shaft 50. In one direction of the rocking movement the right hand set, Figure 4, of the dogs 68 will move the plungers 43 to the right, and in the other direction of movement the left hand set of dogs 68 will move the plungers 43 to the left, if said dogs are in a position where they contact with shoulders 84 formed 110 on the plungers 43, Figure 4. These shoulders 84 are formed on the plungers 43 by means of removing a portion of the plunger, as plainly shown in Figures 4 and 5. However, this contact of the dogs 68 with the shoulders 84 is allowed to take place only 115 when it is desired to move the particular plunger 43 and consequently the valve plunger 39 controlling the hydraulic cylinder whose piston it is desired to operate. The apparatus allows this action to take place, for each particular hydraulic cylinder, when the fingers 70' and 71' are pressed into the notches 61, the timing being correct to 120 register the fingers 70' and 71' and the notches 125 130

61 at the desired times. The rod 69, as will be readily understood, during the movement of the fingers 70' into the notches 61, is forced downwardly to move the dogs 68 5 within the space formed by cutting away a portion of the plunger 43. The right and left hand dogs 68, of course, control the right and left hand movements of the plunger 43, for the particular hydraulic cylinder 10 involved, the movement in one direction sending the fluid into the top of the cylinder and the movement in the other direction sending the fluid into the bottom of the cylinder. Dependent upon the number of actuations 15 per cycle of operations of any particular valve of the six main apparatus valves, the disk 60 is formed with one, two, or the required number of notches 61, each notch 61 allowing for one movement of the means 20 operating the valve piston 39. All of the bars 67 are rocked every time the shaft 50 rotates, and such movement of the bars 67 and the dogs 68 are merely idle ones except when the fingers 70' and 71' intersect the 25 notches 61, in which event the dogs 68 are then in a position to contact with the shoulders 84, due to the trigger action of the dogs under the pull of the springs 73. The action of the right and left hand dogs of each pair 30 are absolutely independent, one of them probably being in an effective position to move the plunger 43 in one direction when the other is in an ineffective position, and vice versa, or both of them being in ineffective positions, and remaining so for a 35 number of revolutions of the shaft 50.

If, for any reason, it is desired or necessary manually to operate the plunger 43, the dogs 68 are locked permanently out of 40 engagement with the shoulders 84 and this is effected by means of the locking-out lever 74 and the locking-out dogs 79 and their co-operating mechanisms hereinbefore described. The dogs 68, of course, are locked 45 out of possible engagement with the shoulders 84 permanently because the pawl fingers 70' and 71' cannot be pressed into the notches 61 or, in other words, the springs 73 cannot perform their normal function, when 50 the notches 61 come into alignment with said fingers. In order to effect the manual operation of the plungers 43, the links 44 are attached to the outer ends of the respective plungers and the respective handles 45 actuated to produce the necessary cycle of 55 gas-making operations.

What I claim is:

1. In apparatus for operating a water gas set, the combination with gas generating apparatus having valves controlling the operation of said apparatus; of hydraulic cylinders connected respectively to said valves of the apparatus, a battery of hydraulic valves connected to said cylinders for controlling 60 the direction of fluid movement there- 65

through, continuously operating valve shifting means for said hydraulic valves, and independent time controlled coupling means consisting of a reciprocable device connected to the valve shifting means and oppositely 70 acting latching means on the reciprocable device for connecting the hydraulic valves in proper sequence to said valve operating means.

2. In apparatus for operating water gas 75 sets, the combination with gas generating apparatus having controlling valves; of a hydraulic cylinder for each valve, a battery of hydraulic valves having outgoing and return connections with said cylinders for controlling the direction of flow of fluid through the cylinders, continuously operating valve mechanism including a reciprocating part and selectively operable and oppositely acting latches for connecting the continuously 80 reciprocating part to a valve at predetermined times and for operation in a predetermined direction.

3. In apparatus for operating a water gas set, the combination with gas generating 85 apparatus including controlling valves; a cylinder for each valve, a controlling valve for each cylinder to regulate the flow of fluid in opposite directions through the cylinders, a continuously operating reciprocating 90 member, oppositely acting pawls carried by said reciprocating member for interlocking engagement with the cylinder controlling valves for opening and closing the same, and independent time controlled means connected to the pawls for selectively moving the same into interlocking engagement with the valves.

4. In apparatus for operating a water gas set, the combination with gas generating 100 apparatus including controlling valves; a hydraulic cylinder for each valve, a hydraulic valve for each cylinder having a return circuit connection therewith and adapted to be operated for controlling the 105 direction of flow of fluid through the cylinders, operating means including a reciprocating member having oppositely acting pawls thereon, a bar connected to each hydraulic valve and having oppositely facing shoulders thereon lying beneath said reciprocating member, means for normally maintaining said pawls out of engagement with said shoulders, and time controlled 110 means for periodically moving said pawls down into contact with said shoulders for moving the hydraulic valve in a desired direction and at the desired time interval.

5. In apparatus for operating a water gas set, the combination with gas-generating 115 apparatus and valves controlling the operation of said apparatus; of hydraulic cylinders connected, respectively, to said apparatus-valves, hydraulic valves controlling 120 the direction of fluid-movement to said cyl- 125 130

inders, respectively, reciprocating pistons for said hydraulic valves, a driven shaft, means connecting said shaft with the several valve-pistons to reciprocate the latter, a second shaft, means secured to the first shaft and adapted periodically to turn said second shaft, means normally rendering said piston-reciprocating means non-effective, and two sets of elements for each hydraulic valve operated periodically by the turning movements of said second shaft to allow the several piston-reciprocating means to function in timed relation.

6. In apparatus for operating a water gas set, the combination with gas-generating apparatus and valves controlling the operation of said apparatus; of hydraulic cylinders connected respectively, to said apparatus-valves, hydraulic valves controlling the direction of fluid-movement to said cylinders, respectively, mechanical movable means for operating said valves, respectively, and including each a reciprocating member and a pair of oppositely operative latch dogs for interlocking engagement with its valve to open and close the same, primary

power means, and movable means actuated by said power means and adapted automatically and selectively to retract said latch dogs and cause some of the movements of said hydraulic-valve-operating means to be ineffective.

7. In apparatus for operating a water gas set, the combination with gas-generating apparatus and valves controlling the operation of said apparatus; of hydraulic cylinders connected respectively, to said apparatus-valves, hydraulic valves controlling the direction of fluid-movement to said cylinders, respectively, mechanical movable means for operating said valves, respectively, primary power means, means actuated by said power means and adapted normally to render ineffective the movements of said hydraulic-valve-operating means, and means controlled by the movements of said power-actuated means and adapted selectively to effect a trigger-release of said hydraulic-valve-operating means.

Signed by me this 14th day of October, 1920.

PIERRE PLANTINGA.
